Amazon.com. Puffin—The Raincoat Jacket—Insulated 12oz Can Cooler / Beer Bottle and Soda Can Insulator. Keeps Drinks and Beverages Cold—Creamsicle. ASIN: B0CH9G3YPB. date first available Sep. 5, 2023 (Year: 2023).*

Primary Examiner — Terry A Wallace*(74) Attorney, Agent, or Firm* — Leber IP Law; Celia H. Leber(57) **CLAIM**

The ornamental design for an insulating sleeve for a beverage container, as shown and described.

DESCRIPTION

FIG. 1 is a perspective view of an insulating sleeve for a beverage container showing our new design;
 FIG. 2 is a front elevation view thereof;
 FIG. 3 is a back elevation view thereof;
 FIG. 4 is a right side elevation view thereof.
 FIG. 5 is a left side elevation view thereof.
 FIG. 6 is a top plan view thereof;
 FIG. 7 is a bottom plan view thereof; and,
 FIG. 8 is an alternate perspective view thereof.

The broken lines in the figures are directed to environment forming no part of the claimed design or show portions of the insulating sleeve for a beverage container that form no part of the claimed design.

The shade lines in the figures show contour and do not claim surface ornamentation or treatment.
